UNITED STATES PATENT OFFICE.

WILHELM B. BRONANDER, OF MONTCLAIR, NEW JERSEY, ASSIGNOR TO INTERNATIONAL CIGAR MACHINERY COMPANY, A CORPORATION OF NEW JERSEY.

CIGAR-BUNCH-FORMING LOOPER.

Application filed December 10, 1923. Serial No. 679,738.

To all whom it may concern:

Be it known that I, WILHELM B. BRONANDER, a citizen of the United States, residing at Montclair, county of Essex, and State of New Jersey, have invented a new and useful Improvement in Cigar-Bunch-Forming Loopers, of which the following is a specification.

This invention relates to a cigar bunch forming looper for cigar making machines.

Certain cigar making machines heretofore known have what is known as a Chianti belt, the purpose of which is to roll a charge of filler into a binder to initially form a bunch; and coacting with said Chianti belt is means for forming a loop therein to enclose the filler, this means including one or two devices engaging the belt. The Chianti belt, with its loop forming device or devices, however, could form bunches of only one shape. The trade demands cigar bunches of many different shapes, and heretofore it has been necessary to change certain parts of the cigar making machines when it was desired to produce cigars of different shapes. The necessity for such changes involved a decrease in quantity production while the change was being made, and consequently an increase of cost.

It has been discovered that these losses can be eliminated by using two looping devices engaging a Chianti belt and relatively adjustable to permit changes in their spaced relation and angularity, so that the mechanism can be adapted to make bunches of many different shapes without machine change or appreciable loss of time. This is the main object of the present invention and with this and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts, Fig. 1 is a side elevation, partly in section, of a bunch forming looper constructed in accordance with the invention; Fig. 2 is a plan view of a part of the structure shown in Fig. 1, certain parts being broken away; Fig. 3 is a cross-sectional view taken on the line 3-3 in Fig. 2; and Figs. 4, 5, 6 and 7 are diagrammatic

views illustrating the operation of the Chianti belt and loop forming mechanism.

In carrying the invention into effect, there is provided a Chianti belt of the usual type, a traveling support to which are attached two belt looping devices engaging the belt to form a loop therein, said looping devices being relatively adjustable in said support to permit changes in their spaced relation and angularity in order to adapt the device for the manufacture of bunches of many different shapes. The parts above mentioned may be widely varied in construction within the scope of the claims, for the particular device selected to illustrate the invention is but one of many possible concrete embodiments of the same. The invention, therefore, is not to be restricted to the precise details of the structure shown and described.

Referring to the drawings, 8 indicates a Chianti belt of the usual type, one end of the belt being fast at 9 to the edge of a rolling table 10; the other end of the belt is fast at 11 to a drum 12 which is rotated for belt tensioning purposes by means of a chain 13 operated by a cam controlled weight 14, the control not being shown but well known in the art.

There is further provided a traveling support 15 which is moved over the Chianti belt 8 by means of a slide 16 mounted in a slideway formed by bars 17 located along one side of the table 10, and suitably supported from the main frame of the cigar machine in connection with which the device is used. This slide is reciprocated by means of a link 18, one end of which is pivoted thereto, the other end of the link being pivoted to a cam actuated lever 19 deriving its motion from a cam on one of the cam shafts of the machine in connection with which the device is used. The support 15 is clamped to a post 20 journaled in a suitable bearing 21 which has two arms 22-22 projecting therefrom, the free ends of the arms being pivoted at 23 to the slide 16. The support is further provided with cam bowls 24-25 tracking respectively in cam grooves 26-27 formed in a stationary cam plate 28 bolted to uprights 29-30 supported by the main frame of the cigar machine in connection with which the device is used. The cam plate 28, with its grooves 26 and 27, controls the path of the support as the latter moves over the table 10, and the path of the sup-

port may be quickly changed by substituting for the cam plate 28 another one having differently shaped cam grooves determined in accordance with the shape of the cigar bunch 5 the production of which is desired. The structure so far described is old and well known in the art and since a more detailed description of the same is unnecessary to a full understanding of the present invention, 10 it is omitted in the interest of brevity and clearness.

The support 15 is provided with two belt looping devices engaging the belt 8 and relatively adjustable in said support to 15 permit changes in their spaced relation and angularity to accommodate cigar bunches of different diameters and different longitudinal contour. As shown, one of these devices is mounted in fixed position relative to the support and the other is adjustably mounted relative thereto, and the devices underlie the support. With this 20 end in view, the support is provided with depending lugs 31-32 in which are fixed rods 33, and on and between the ends of these rods is mounted a roller 34. The roller 34 is therefore mounted in fixed position relative to the support, but will of course follow the tortuous path of the support as the latter moves over the table 10.

The support 15 is further provided with slots 35-35, and in each of these slots is mounted a bolt 36 which serves to lock a rod 37 in a block 38 depending from the support 15. Mounted upon adjacent ends and between the rods 37 is a roller 39.

The roller 39 may be quickly adjusted to vary its spaced relation and angularity with respect to the relatively fixed roller 34 to accommodate bunches of different diameters and different degrees of taper when they are in process of formation, as indicated in Fig. 6.

By means of the structure described, the 45 device may be very quickly adjusted to cause the Chianti belt to form bunches of different diameters and different longitudinal contours in order that many differently shaped bunches may be made on the 50 same machine by simple readjustment of the looper and substitution of one stationary cam for another, the latter being unnecessary in many cases.

What is claimed is:

55 1. A bunch forming looper comprising

a Chianti belt, a traveling support, and two belt looping devices engaging said belt and relatively adjustable in said support to permit changes in their spaced relation and angularity.

60 2. A bunch forming looper comprising a Chianti belt, a traveling support, and two belt looping devices engaging said belt and relatively adjustable in said support to permit changes in their spaced relation and angularity, one of said devices being mounted in fixed position relative to said support and the other being adjustably mounted relative to said support.

65 3. A bunch forming looper comprising a Chianti belt, a traveling support, and two belt looping devices engaging said belt and relatively adjustable in said support to permit changes in their spaced relation and angularity, said devices being mounted to 70 underlie said support.

75 4. A bunch forming looper comprising a Chianti belt, a traveling support, and two belt looping devices engaging said belt and relatively adjustable in said support to permit changes in their spaced relation and angularity, said devices including rods engaging said support, and rollers rotatable on said rods.

80 5. A bunch forming looper comprising a Chianti belt, a traveling support, and two belt looping devices engaging said belt and relatively adjustable in said support to permit changes in their spaced relation and angularity, said support being provided 85 with slots in which one of said devices is adjustably mounted.

85 6. A bunch forming looper comprising a Chianti belt, a traveling support, and two belt looping devices engaging said belt and relatively adjustable in said support to permit changes in their spaced relation and angularity, said support being provided with depending lugs in which both ends of 90 said devices are mounted.

95 7. A bunch forming looper comprising a Chianti belt, a traveling support, and two belt looping devices engaging said belt and relatively adjustable in said support to permit changes in their spaced relation and angularity, and stationary means for controlling the path of said support.

100 In testimony whereof, I have signed my name to this specification.

WILHELM B. BRONANDER.
